Bartlett & Hawes.

UNITED STATES PATENT OFFICE.

ALBERT P. HODGE, OF WINSTED, CONNECTICUT, ASSIGNOR TO WILLIAM L. GILBERT CLOCK COMPANY, OF WINSTED, CONNECTICUT, A CORPORATION OF CONNECTICUT.

CLOCK.

Application filed December 22, 1922. Serial No. 603,397.

To all whom it may concern:

Be it known that I, ALBERT P. HODGE, a citizen of the United States, residing at Winsted, county of Litchfield, State of Connecticut, have invented a certain new and useful Improvement in Clocks, of which the following is a full, clear, and exact description.

My invention relates to clocks and more particularly to clocks of the type having a casing provided with a removable back cover by which the works are carried, and has for its principal object to provide a clock of this type of novel and improved construction in which the main driving gear, its arbor and the main spring may be easily removed and replaced. A further object is to enable the replacement of a broken main spring without disassembling the works of the clock mechanism as a whole.

The several features of the invention will be clearly understood from the following description and accompanying drawings, in which,—

Figure 1 is a side elevation, partly in section, of a portion of the clock mechanism and the back cover of a clock embodying my invention;

Fig. 2 is a sectional view, partly in elevation, taken on the line 2—2 of Fig. 1;

Fig. 3 is a sectional elevation taken on the line 3—3 of Fig. 1;

Fig. 4 is a detail side elevation, partly in section and on an enlarged scale, of a portion of the clock mechanism, but showing a modification of the bearing for one end of the main spring arbor; and

Fig. 5 is a detail side elevation of the outer end portion of the main spring.

The clock illustrated in the drawings is provided with a removable back casing cover 2 to which is detachably secured the clock mechanism and its supporting frame. This frame comprises front and rear frame members 4 and 6, respectively, that are connected by posts 8. The forward end of the posts 8 are rigidly secured to the front frame member 4 in the usual manner, and the rear ends of the posts 8 extend through apertures in the rear frame member 6 and are reduced in diameter so as to form shoulders 10 that cooperate with washers and nuts 12 screw-threaded on said reduced ends to securely clamp the rear frame member 6 between them, and thus secure the front

and rear frame members together. The reduced ends of the posts 8 extending beyond the nuts 12 are passed through apertures in the back cover 2 and nuts 14 are screw-threaded on their extreme ends so as to cooperate with the nuts 12 to clamp the back cover between them and thus detachably secure the clock mechanism and its frame to the back cover 2.

The parts of the clock mechanism illustrated in the drawings comprise a driving gear 16, its arbor 18, and a main spring 20. The forward end of the arbor is reduced in diameter and extends through and is journaled in an aperture in the front frame member 4, and in accordance with the present invention the rear end of the arbor is reduced in diameter to form a shoulder 22, and in the constructions illustrated in Figs. 1 and 2 this reduced end extends through and is journaled in a bearing member 24 which is secured by rivets 26 to the inner face of the back cover, the rivets extending through laterally extending ears on opposite sides of said member. The arbor 18 is of the usual construction, the shoulder 22 of the arbor being arranged substantially in the plane of the forward side of the rear frame member. The end of the bearing member 24 extends up to this shoulder so as to prevent rearward axial movement of the arbor. The aperture in the bearing member 24 registers with an opening in the back cover, and the reduced rear end of the arbor extends through this opening so as to enable a winding key 27 (indicated by broken lines) to be applied thereto. The bearing member 24 is axially counter-sunk on its rear side so as to enable the shank of the winding key to extend further up on the end of the arbor.

The main spring 20 is applied to the arbor 18 in the usual manner, the inner end of the spring being detachably secured to the arbor by means of a lug 28 on the arbor which is received in an aperture in the spring. In the illustrated construction, however, novel and improved means is provided for detachably securing the outer end of the main spring in place, the means being such that the end of the spring may be easily attached and detached without disconnecting the frame members 4 and 6. As shown, this means comprises a plate 29 which is secured to the outer end of the main

spring by means of rivets 30. The plate is provided with a depending hook member or lug 31 on its lower longitudinal edge which, when the spring is in place on its arbor, is 5 adapted to be hooked over the end wall of an elongated slot 32 in the rear frame member 6. With this construction it will be apparent that the tension of the main spring will 10 serve to firmly hold the hook member 31 in locking engagement with the end wall of the slot 32, and that the end of the spring may be easily detached from the rear frame member when desired, by pulling the end of the spring longitudinally so as to disconnect the 15 hook member 31 from the wall of the slot 32 and then lifting the hook member out of the slot.

The clock illustrated in the drawings is provided with a striking mechanism which, 20 as shown, comprises a driving gear 34, its arbor 36 and main spring 38. When the clock is thus provided with a striking mechanism, the outer end of the striker main spring 38 preferably is detachably secured 25 to the front frame member 4 in the same way as the main spring 20 is secured to the rear frame member 6, as above described, and the rear reduced end of the arbor 36 extends through and is journaled in a bearing member 40 that is secured to the rear frame member 6 and corresponds to the bearing member 24.

With the construction above described it will be apparent that upon removing the 35 winding keys and the nuts 14 from the frame posts 8, the clock mechanism and frame may be removed as a whole from the back casing cover 2, the rear ends of the arbors 18 and 30 being slipped out of the bearing 40 members 24 and 40. The arbor 18, driving gear 16 and main spring 20 may then be easily removed from and replaced as a unit on the clock mechanism frame upon disengaging the outer end of the spring from the 45 rear frame member, the rear frame member being cut away at 42 so as not to interfere with the removal of these parts. Thus the arbor, driving gear and main spring of the clock mechanism may be easily removed for 50 the purpose of replacing a broken spring or for repair without in any way displacing other parts of the clock mechanism. It will also be apparent that as the arbor, driving gear and main spring of the striker 55 mechanism are constructed and arranged similar to said corresponding parts of the clock mechanism, that these parts may likewise be easily removed and replaced.

In the construction illustrated in Fig. 4 60 the bearing member for the rear end of the arbor 18 consists of an annular block 44 which is rigidly secured to the rim of a circular aperture in the back casing cover 2. The bearing block is provided with a reduced rear end portion that is passed

through the circular aperture in the back casing cover with the shoulder at the upper end of the reduced portion abutting the inner face of the cover, and then the end of the block projecting beyond the cover is spiked 70 or headed over so as to cooperate with said shoulder to securely grip the rim of said aperture.

As will be evident to those skilled in the art my invention permits of various modifications without departing from the spirit thereof or the scope of the appended claims. 75

What I claim is:

1. A clock of the type having its casing provided with a removable back cover having, in combination, a frame having front and rear frame members, means for detachably securing said frame to the back cover, a clock mechanism comprising a driving gear, 80 an arbor for said gear having one end journaled in the front frame member, a bearing member for the other end of said arbor secured to said back cover and through which said end extends, and a main spring having one end detachably connected with said frame and its other end connected with said arbor, said parts being constructed and arranged so as to enable the arbor, gear and spring to be removed from said frame when 85 said frame is removed from the cover. 90

2. A clock of the type having its casing provided with a removable back cover having, in combination, a frame having front and rear frame members, means for detachably securing said frame to the back cover, a clock 100 mechanism mounted in said frame comprising a driving gear, an arbor for said gear having one end journaled in the front side frame and having its other end reduced in diameter so as to form a shoulder in substantially the plane of the rear side frame, a bearing member secured to the cover and through which said reduced end of the arbor extends, the forward end of the bearing member extending to said shoulder on the 105 arbor to prevent rearward axial movement of the arbor, and a main spring having one end detachably connected with said frame and its other end connected with the arbor, said parts being constructed and arranged 110 so as to enable the arbor, gear and spring to be removed from said frame when the frame is removed from the cover. 115

3. A clock of the type having its casing provided with a removable back cover having, in combination, a frame having front and rear frame members and connecting parts having their rear ends reduced in diameter and extending through apertures in the rear frame member and the back cover, 120 nuts screw-threaded on the reduced end of each of the posts arranged to clamp the cover between them so as to detachably secure said frame to the cover, a clock mechanism mounted in said frame comprising a driv- 125 130

ing gear, an arbor for said gear having one end journaled in the front side frame, a bearing member for the other end of said arbor secured to the back cover and through which said end extends, and a main spring having one end detachably connected with said frame and its other end connected with said arbor, said parts being constructed and arranged so as to enable the arbor, gear and spring to be removed from said frame when said frame is removed from the cover.

4. A clock having, in combination, a frame comprising front and rear members,

and a clock mechanism mounted therein comprising a removable arbor, a driving gear on said arbor, a main spring having one end secured to the arbor and its other end provided with a lateral forwardly projecting hook, one of said frame members having a slot adjacent to the outer end of said spring, said hook passing through said slot and being hooked over the wall of said slot so as to detachably secure said end of the spring to said frame member.

ALBERT P. HODGE.
